(57) **CLAIM**

The ornamental design of a radio controlled model stand, as shown and herein described.

DESCRIPTION

FIG. 1 is an isometric view of a radio controlled model stand showing my new design;

FIG. 2 is a side elevational view thereof;

FIG. 3 is an opposite side elevational view thereof;

FIG. 4 is a front view thereof;

FIG. 5 is a rear view thereof;

FIG. 6 is a top view thereof;

FIG. 7 is a bottom view thereof; and,

FIG. 8 is a perspective view thereof shown with environment. The broken lines shown in the drawings are for illustrative purposes only and do not form part of the claimed design. The surface shading (shown in uniformly spaced horizontal and vertical lines) does not represent a pattern.

The drawings disclose the configuration of the a radio controlled model stand.
